UNITED STATES PATENT OFFICE

HENRY LEITNER, OF TUNBRIDGE WELLS, ENGLAND.

DYNAMO.

1,283,534.

Specification of Letters Patent.

Patented Nov. 5, 1918.

Application filed January 23, 1915. Serial No. 3,926.

To all whom it may concern:

Be it known that I, HENRY LEITNER, a subject of the King of Great Britain, residing at Montacute House, 45 Broadwater 5 Down, Tunbridge Wells, Kent, England, have invented new and useful Improvements in or Relating to Dynamos, of which the following is a specification.

My invention relates to means for regulating the output of dynamo machines designed to be driven at variable speeds. In such machines when used in conjunction with accumulators for train lighting and the like, it is well known that it is advisable 10 gradually to reduce the output of the machine as the voltage of the battery rises on charge, so that when the battery is fully charged the charging current is reduced practically to zero or to a very low value. 15 It is also advantageous to limit the voltage of the machine when the lamps are in circuit, so that it may not rise much above the normal lamp voltage. It has been common practice to reduce the output of such machines by introducing a resistance or resistances into the shunt field circuit, or, in 20 general, by diminishing the field flux by reducing the current in the exciting coils. This method, however, is not entirely satisfactory because its action is to a certain extent interfered with by the characteristics imposed upon the machine due to the necessity of compensation for variations in speed.

Now, according to my invention I dispense wholly or partially with the necessity of introducing resistance into the field circuit or into any equivalent circuit, and in lieu thereof I provide the dynamo with an additional series winding, in series with the 25 supplied circuit, and so connected that the current therein shall act on the field flux so as either to oppose or to assist the normal flux, under conditions hereinafter set forth. This series winding may be on one or more 30 main poles, or on interpoles, depending on the type of variable speed machine to which the invention is applied. I further provide means whereby this series winding may be short-circuited either wholly or in part or 35 in sections. Such means may consist of any known form of electro-magnetic switch or switches designed to operate at predetermined voltages so as to close or open the said short-circuit or short-circuits.

50 My invention is applicable to variable speed dynamos of all classes, either with

or without subsidiary brushes or short-circuited brushes, or to such dynamos already provided with a reverse compound winding and either with or without wound 60 or unwound interpoles, or in which the regulation for speed variations is due to armature reactions, and to all known forms of variable speed dynamos in general.

An example of one type of variable speed 65 dynamo to which my invention is applicable is described in the specification of my British Patent No. 9,655 of 1905, and in order that my invention may be fully understood I will describe its application to this type of 70 machine by reference to Figures 1 to 4 of the accompanying diagrammatic drawings, in which:—

Fig. 1 is a view showing one arrangement 75 of such a dynamo provided with an additional series field winding, and an electro-magnetic device for opening or closing a short-circuit on the same.

Figs. 2 and 3 illustrate two modifications 80 of the arrangement, and

Fig. 4 illustrates a further application of 85 my invention.

Referring first to the arrangement illustrated in Fig. 1, A is a dynamo having a shunt field circuit B excited from a main 85 brush C, and one subsidiary brush D. E is the battery of accumulators, F represents the lamps in the supplied circuit, and G an electro-magnetic cut-in and cut-out device of the well known type for making and breaking 90 the circuit of the dynamo A with the battery E and lamps F.

a is the reverse series winding in the field circuit of the dynamo A, the said winding being in series in the dynamo circuit to both 95 battery E and lamps F. *b* is an electro-magnetic device comprising a fine wire or voltage coil *c* connected through the contacts of said device across the main brushes C and C¹ of the dynamo, the connection being 100 made preferably through a contact *d* on the automatic cut-in and cut-out device G. The electro-magnet or solenoid coil *c* has an armature or core *e* and a short-circuiting bar *f* which, when in its normal position, serves 105 to close two contacts *g*, *h* whereby the series field winding *a* of the dynamo A is short-circuited. The electro-magnetic device *b* is calibrated by means of a spring or otherwise, or it may act by gravity, so that at a predetermined voltage the armature or core *e* is 110 attracted, the short-circuit bar *f* lifted, and

the short-circuit thereby removed from the field coil a . When this is done the output of the dynamo is automatically reduced to any required value depending on the number 5 of ampere-turns on the series winding.

The shunt field winding of the dynamo is shown in Fig. 1 connected as what is usually termed a "short" shunt, but in some cases it is advantageous to connect it as a "long" 10 shunt, that is to say, that one end, instead of being connected directly to the main brush C , would be connected to the farther side of the series winding a . Such an arrangement is disclosed in Fig. 3 when the 15 lamp switch H is in its dotted line position as hereinafter described.

The subsidiary brush dynamo shown in Fig. 1 is given in its simplest form by way of illustration merely. The invention is applicable, however, to all known forms of 20 such dynamos whether with or without additional windings, or with or without interpoles.

Instead of inserting the series field winding in the dynamo circuit to both battery and lamps as shown in Fig. 1, I may insert it in the battery circuit only. Such an arrangement is shown in Fig. 2 where the series winding a will be seen to be in the 25 branch circuit from the dynamo to the battery E , but not in circuit between the dynamo and the lamps F .

With the arrangement of the circuits as shown in Fig. 2 it will be seen that when the 30 lamps are switched on, and the short-circuit is removed from the series field winding a , a condition of things may be established in which the battery may be made to "float"; any increase in the voltage of the dynamo, 35 tending to cause a charging current to pass into the battery, being immediately checked by the reverse current in the series winding a , while any tendency of the battery to discharge will cause a direct current in the series winding which will immediately boost 40 up the voltage of the dynamo.

The automatic cut-in and cut-out device G may in some cases as shown in Fig. 2 be provided with a pair of contacts l, m which, 45 when the device is in the "off" position, serve to short-circuit the series winding a when the lamps are "on", but not when they are "off", and for this purpose the short-circuiting circuit may be interconnected with 50 the lamp switch H .

Referring now to Fig. 3, this shows an arrangement of circuits in which the series winding a is employed partly in a direct sense and partly in a reverse sense, that is 55 to say, at one time to assist the normal field flux, and at another time to oppose it. This is effected in the following manner:

One of the main brushes of the dynamo A , say the positive brush C , is connected in the 60 first instance to the main lamp switch H

which, when in the "on" position, enables the current to pass through the contact i to the battery E , and through a branch circuit to the series winding a , and thence through the contact k of the lamp switch to the lamp circuit. Any discharge from the battery to the lamps will be in the same direction as the dynamo current through the series winding a , and this direction is direct, that is to say, it assists the normal field flux, and increases 70 the excitation in proportion to the lampload. If, now, the lamp switch be placed in the "off" position, the positive dynamo brush C is disconnected from the contact i and connected to the contact j , and the contact which 75 was formerly on k is removed therefrom. By this movement the lamp circuit is opened, and the current from the dynamo to the battery passes in a reverse direction through the series winding a , thereby limiting the output 80 of the dynamo, and checking any tendency for the current to rise above the predetermined limit.

The series winding may be short-circuited by means of an electro-magnetic switch b , 85 as previously described, the said switch only operating to remove the short-circuit at a predetermined voltage. Should it be advisable to reduce still further the charging current with a further rise of voltage, a second electro-magnetic switch n may be employed, 90 calibrated for the higher voltage. This switch may remove a short-circuit from a resistance o placed in the shunt field circuit of the dynamo, or in any circuit the insertion of resistance in which, or the modifying of which, will limit the output of the dynamo, such limitation being now sufficient to 95 reduce the output practically to zero, or thereabout, since the battery is now fully 100 charged. This switch may advantageously be energized only when the first switch b has operated, as, for example, through the contacts p, q .

In some cases it is advisable when the 110 lamps are "on" to permit of the second electro-magnetic switch n operating simultaneously with the first switch b . This may be accomplished, for example, by inserting a resistance r in series with the winding of the 115 switch, so that when this resistance is short-circuited the switch will act more strongly and, therefore, at a lower voltage, *i. e.*, at the predetermined voltage of the first switch, but if the resistance is not short-circuited it will 120 not act until the higher predetermined voltage has been reached. The short-circuiting may advantageously be done by the lamp switch when in the "on" position, as, for example, through the contact s .

It is advantageous also to insert a resistance t in series with the winding of the first electro-magnetic switch, and to short circuit this with the automatic cut-in and cut-out device G when in the "on" position. Such a 125 130

resistance will prevent any sudden rise of voltage of the dynamo when at the cutting-in speed from operating the switch *b* before *G* has actually operated.

5 Furthermore, it is also advantageous so to design the electro-magnetic devices or short-circuiting switches that, while they are calibrated to operate at predetermined voltages to remove the short-circuit, they shall not 10 come off so as to renew the short-circuit except at very low voltages. This will prevent "hunting" of the automatic cut-in and cut-out device due to the cutting-out speed of the dynamo being raised owing to a weak- 15 ened field.

The series winding *a*, instead of being placed on the main poles as shown in the figures of the drawings above described, may, in some classes of machines, be placed on 20 subsidiary or interpoles, whether these poles have or have not other windings provided to compensate for speed variations. The present additional series winding will be superimposed upon any such speed regulation.

25 Fig. 4 gives, by way of example, an illustration of such an arrangement applied to a variable speed machine having the main fields excited by means of two subsidiary brushes, and the series winding placed upon 30 unwound subsidiary or interpoles. *A* is the dynamo having two main brushes *C* and *C'* and two subsidiary brushes *D* and *D'*, main field coils *B* and *B'*, and a series winding *a*, *a'* on subsidiary poles placed between the 35 main poles. Any of the auxiliary apparatus shown and described in the other drawings, or above referred to, may be used in this combination, and the series winding *a*, *a'* is so arranged that when it is required to re- 40 duce the output of the machine, the current will pass in such a direction through it as to assist the cross-flux produced by the magnetization of the armature by armature current, as is well understood.

45 I do not confine myself to the particular arrangements shown in the accompanying drawings, which are merely diagrammatic and by way of example only. In particular, the electro-magnetic devices herein shown 50 may be varied, modified, or combined in ways which will be obvious to those skilled in the art, as also will be the method of application of the invention to other types of variable speed machines than those particularly referred to and illustrated in the 55 drawings.

Having now fully described and ascertained my said invention and the manner in which it is to be performed, I declare that 60 what I claim is:—

1. The combination with a generator which is inherently self regulable for variations in speed, of an auxiliary series field superimposed upon the main field of said generator to afford further regulation of

said generator and means sensitive to variations in the voltage of said generator to vary the effectiveness of said auxiliary field.

2. The combination with a generator which is inherently self regulable for variations in speed, of an auxiliary series field superimposed upon the main field of said generator to afford further regulation of said generator, a storage battery to be supplied by said generator and connections 70 placing said auxiliary field in series between said generator and said battery to buck or boost the main field of said generator accordingly as the generator voltage or battery voltage predominates.

3. The combination with a generator which is inherently self regulable for variations in speed, of an auxiliary series field superimposed upon the main field of said generator, electro-responsive means included 85 in circuit with said generator to vary the effectiveness of said auxiliary field and means controlling said auxiliary field to utilize the same for alternatively bucking or boosting the main field of said generator.

4. The combination with a generator which is inherently self regulable for variations in speed, of a superimposed auxiliary series field thereof, electro-responsive means associated with said generator to vary the 95 effectiveness of said auxiliary field for regulation of said generator, lamps and a battery to be supplied by said generator and circuit controlling means for said auxiliary field, lamps and battery to effect reversals 100 of the flow of current through said auxiliary field for boosting and bucking the main field of said generator under different conditions.

5. The combination with a generator 105 which is inherently self regulable for variations in speed, of a superimposed auxiliary series field therefor, electro-responsive means associated with said generator to vary the effectiveness of said auxiliary field for regulation of said generator, lamps and a battery to be supplied by said generator and circuit controlling means for said auxiliary field, lamps and battery to direct the current flow through said auxiliary field for boosting 110 the main field of said generator when said lamps draw upon said battery and for bucking the main field of said generator when said generator supplies said battery 115 with said lamps disconnected.

6. The combination with a generator which is inherently self regulable for speed variations, of a superimposed auxiliary series field therefor, electro-responsive means associated with said generator to vary the 125 effectiveness of said auxiliary field, lamps and a battery to be supplied by said generator, and means for connecting said auxiliary field between battery and lamps for boosting relation with respect to the main field of 130

said generator and for connecting said auxiliary field between said generator and said battery and reversing the relation of said auxiliary field with respect to the main field of said generator, when said lamps are disconnected.

7. In combination, a variable speed generator having a superimposed auxiliary series field winding, a supply circuit therefrom, electro-responsive means connected across said circuit for controlling said auxiliary field winding according to the voltage conditions of said circuit, lamps and a battery connected in different branches of

said circuit and means for placing said 15 winding in the lamp branch of said circuit to receive a uni-directional flow of current from said generator and said battery and to alternatively place said winding between said generator and said battery for reversal 20 of the current flow thereto from said generator while maintaining the same relation between said winding and said battery.

HENRY LEITNER.
